US0D1113964S

(12) **United States Design Patent** (10) **Patent No.:** **US D1,113,964 S**
(45) **Date of Patent:** **** Feb. 17, 2026**

(54) **DISPLAY SCREEN WITH GRAPHICAL USER INTERFACE OF A GAMING MACHINE**

(71) Applicant: **LNW Gaming, Inc.**, Las Vegas, NV (US)

(72) Inventor: **Yanis Tsombanidis**, Las Vegas, NV (US)

(73) Assignee: **LNW Gaming, Inc.**, Las Vegas, NV (US)

(**) Term: **15 Years**

(21) Appl. No.: **30/000,488**

(22) Filed: **Apr. 22, 2025**

Related U.S. Application Data

(63) Continuation of application No. 29/896,802, filed on Jul. 7, 2023, now Pat. No. Des. 1,075,808.

CLAIM

The ornamental design for a display screen with graphical user interface of a gaming machine as shown and described.

DESCRIPTION

The FIGURE is a front view of a display screen with graphical user interface of a gaming machine showing my new design.

The peripheral broken line shows the display screen and the boundary of the claim, and forms no part of the claimed design. The remaining broken lines depict portions of the graphical user interface that form no part of the claimed design.
